METALLURGICAL METHOD AND APPARATUS

Filed July 29, 1941

FIG. 1.

FIG. 2.

FIG. 3.

INVENTOR

Harry Heuer

BY
Augustus B. Strongbow
ATTORNEY.

WITNESS:

Bob Kitchel

erally cylindrical hollow body mounted for movement of rotation about its horizontal axis, and having at its end a hollow semi-cylindrical extension communicating with the interior of the body, and disposed eccentrically in respect to said axis, and having heads closing the end of the body and the end of the extension and a deck closing the extension and joining the heads.

3. Metallurgical apparatus comprising a hollow vessel mounted for oscillation, and comprising a cylindrical wall provided at its ends with semi-cylindrical wall extensions, and provided at the ends of the cylindrical wall and of the semi-cylindrical wall extension with semi-circular heads, and provided at the extensions with decks joining the heads, the extensions being spaced 90° apart, whereby when the vessel is nearly full of molten metal and supernatant slag and oscillated, there is endwise flow which presents fresh contact surfaces between the metal and the slag. 20

4. Metallurgical apparatus comprising a hollow vessel mounted for circular movement, and

the 1970s, when the number of people in the United States who were foreign born reached a record high of 37 million, or 13 percent of the total population. The number of foreign born in the United States has since declined to 31 million, or 10 percent of the total population. The foreign born population in the United States is now 45 percent male and 55 percent female, and the median age is 31. The foreign born population in the United States is now 45 percent male and 55 percent female, and the median age is 31.

and the 18th century, the first half of which was a period of relative peace and prosperity, the second half was one of increasing political and social instability, and finally the last half was one of revolution and civil war. The 19th century was a period of relative peace and prosperity, the 20th century was one of revolution and civil war, and the 21st century is likely to be one of revolution and civil war. The 22nd century is likely to be one of revolution and civil war, and the 23rd century is likely to be one of revolution and civil war.

comprising a cylindrical wall having at one end a head, and provided at its other end with a semi-cylindrical wall extension, and provided at that end of the cylindrical wall and at the end of the semi-cylindrical extension with semi-circular heads, and provided at the extension with a deck joining said last mentioned heads.

5. A metallurgical apparatus comprising a shell for molten metal and supernatant slag mounted for oscillation about its horizontal axis, said shell comprising a mid-portion and an enclosed axially disposed end extension of less cross section than the cross sectional area of said mid-portion, and communicating with the interior of the shell, and arranged eccentrically in respect to said axis, whereby when the shell contains molten metal and supernatant slag to a level above the entrance to the extension, and the shell and extension is oscillated, there is endwise flow principally of slag presenting fresh contact surfaces between the metal and the supernatant slag.

HARRY HEUER.
